UNITED STATES PATENT OFFICE

EDGAR D. ROSENBERG, OF SAN FRANCISCO, CALIFORNIA, ASSIGNOR OF ONE-HALF TO
RAPHAEL SAMPSON, OF OAKLAND, CALIFORNIA

ICE CUBE REMOVER

Application filed December 11, 1929. Serial No. 413,223.

In partitioned ice trays of the type commonly employed in household electric refrigerators, difficulty is often encountered in attempting to release ice cubes from the tray. A common method of separating the cubes from the tray is to pour warm water about the tray, but this method is unsanitary as well as inconvenient for the reason that the ice cubes are scattered about and frequently fall in unclean places. In the practice of my invention, the cubes are released in a convenient, sanitary and expeditious manner and a receptacle is provided for catching the released cubes.

It is an object of this invention to devise means for releasing ice cubes from a tray.

Another object is to devise a tray from which ice cubes may be removed in a convenient and sanitary manner.

Another object is to devise means for heating the walls of an ice cube tray.

Another object is to devise electrical means for facilitating removal of ice cubes from a tray.

A further object is to devise means for completing the operating electrical circuit in a tray of this type.

A further object is to devise means for automatically breaking the operating electrical circuit when the cubes have been released.

A further object is to devise means for facilitating the collection and disposal of released ice cubes.

A still further object is to devise means for protecting the electrical terminals of a tray of this type from injury and from the formation of ice and frost thereon.

Other objects and advantages will appear from the following detailed description of a preferred embodiment of my invention.

Attention is directed to the accompanying drawings in which:

Fig. 1 is a perspective view of the ice tray of this invention.

Fig. 2 is a cross-sectional view taken on the line 2—2 of Fig. 1.

Fig. 3 is a detail cross-sectional view taken on the line 3—3 of Fig. 1.

Fig. 4 is a sectional view showing a modification of one of the heating elements of the invention.

Fig. 5 is a cross-section taken on line 5—5 of Fig. 4.

Fig. 6 shows a modification in perspective.

Fig. 7 is a perspective view showing the chamber, ice tray and scoop of this invention in assembled relation.

Fig. 8 is a cross-section taken on line 8—8 of Fig. 7.

Fig. 9 is a cross-section taken on line 9—9 of Fig. 7.

Fig. 10 is a perspective view of the scoop of the invention.

Fig. 11 is a detail view showing a protective covering for the terminals of the heating elements.

Referring to the drawings, an ice tray 10 is shown having longitudinal partitioning walls 11 and transverse partitioning walls 12. Walls 11 are formed from a sheet of metal bent back upon itself, as shown in Fig. 3, the sides 13 and 14 of each wall being separated at their lower ends to form a sheath for an electrical heating element 18. Strips 16 and 17 of mica or other heat resisting insulating material are disposed within the sheath and around element 18 to insulate element 18 from walls 13 and 14 of the sheath and from the inside plate 15 of the base of the tray. Plate 15 is bent to form the inside of the base and the surrounding walls of the tray and has a rolled over edge 19. Surrounding plate 15 and forming the outside shell of tray 10 is a sheet metal casing 20.

A space is provided between inside plate 15 and outside casing 20 for housing heating elements 24 disposed between insulating sheets 21 and 22. Casing 20 is pressed inwardly at 90

85

80

75

70

65

its edges 23 and secured in any suitable manner to plate 15.

Heating elements 18 and 24 are provided with insulated terminals 25 and 26 which are 5 adapted to be connected to a source of current. When a circuit is completed for heating elements 18 and 24, partitioning walls 11 and 12 and inside casing 15 of the tray become heated and melt the adhering surfaces 10 of the ice cubes allowing removal of the ice cubes by inverting the tray. Walls 11 are heated directly by heating elements 18 and walls 12 become hot by conduction of heat from walls 11. Walls 11 and 12 are secured 15 at their extremities to inside casing 15 of the tray and therefore will not be disturbed when the tray is inverted.

In Figs. 4 and 5 a modification has been shown in which each heating element is in 20 the form of a coil. In this construction, sides 13 and 14 of each longitudinal partitioning wall form at their lower end a sheath suitable for housing an electrical heating element 27 of helical shape. Surrounding element 27 is a refractory tube 28 for insulating element 27 from the adjacent metallic parts of the tray. In this modification the partitioning walls of the tray become hot by 25 conduction of heat from heating element 27.

30 In Fig. 6 I have shown a modification in which a heating element 29 having terminals 30 and 31 is located in a chamber adapted to receive an ice cube tray. In this modification the tray is inserted in the chamber until 35 the adhering surfaces of the ice cubes melt and upon withdrawal of the tray the ice cubes may be removed by inverting the tray.

A chamber 32 provided with a scoop 33 is shown in Figs. 7, 8 and 9 and is adapted to be 40 used in conjunction with the tray shown in Fig. 1. When tray 10 is inverted and pushed into chamber 32 along a shelf 37, contacts 25 and 26 of heating elements 18 and 24 engage complementary terminals 34 located inside of 45 the chamber. Leads 35 and 36 connect terminals 34 to a suitable source of current which preferably is the local source of commercial current. When the adhering surfaces of the 50 ice cubes have been melted the ice cubes drop into scoop 33. Scoop 33 is provided with a handle 38 and a relatively narrow end portion 39 to facilitate removal and disposal of the ice cubes. A spring 40 is located at the rear end of chamber 32 and is adapted 55 to abut against the end of tray 10 when it is inserted in the chamber. Spring 40 is of sufficient size to urge tray 10 outwardly and thereby disengage terminals 25 and 26 from connectors 34 when the tray is empty, but is 60 of insufficient strength to move the tray when the tray is loaded with ice cubes. Spring 40 prevents waste of current by breaking the contacts when the heating elements have performed their function and also affords a visual 65 indication to the operator by causing the

tray to extend from the chamber when the cubes have been released.

For keeping terminals 25 and 26 free from the formation of ice or frost while the tray is in a refrigerator and for preventing injury to the terminals, I have shown in Fig. 11 a protective covering 41 for terminals 25 and 26. Protective covering 41 may be a dummy socket which fits securely over terminals 25 and 26 and it may or may not be secured to the rear wall 42 of a refrigerator. If desired an operative socket secured to wall 42 may be employed for this purpose and for the purpose of enabling the tray 10 to be thawed out on those occasions when the tray has become frozen in the refrigerator. In the latter case, some form of switch (not shown) would be desirable to turn the current to the heating elements off and on so that the heating elements may be made inoperative while ice is being made.

In the operation of the device, tray 10 is inverted and inserted in chamber 32 whereupon a circuit is completed for heating elements 18 and 24. The ice cubes are released and drop into scoop 33 and spring 40 then becomes effective to push tray 10 outwardly to break the connections to the heating elements.

It is to be understood that I do not limit myself to the specific embodiment of the ice cube remover shown and described herein, as the invention, as set forth in the following claims may be embodied in a plurality of forms.

I claim:

1. In a device for freeing ice cubes, a tray having a plurality of partitions, electrical heating elements disposed within the walls of said partitions, plug terminals for said heating elements extending from one end of said tray, a chamber adapted to receive said tray and socket connectors in said chamber adapted to register with said plug terminals.

2. In a device for freeing ice cubes, a tray having a plurality of partitions, electrical heating elements disposed within the walls of said partitions, plug terminals for said heating elements extending from one end of said tray, a chamber adapted to receive said tray and socket connectors in said chamber adapted to register with said plug terminals, and a removable scoop in said chamber for collecting released ice cubes.

3. In a device for freeing ice cubes, a tray having a plurality of partitions for molding ice cubes, electrical heating elements disposed within the walls of said partitions, a chamber adapted to receive said tray in an inverted position, electrical contacts in said chamber for said heating elements, spring means in said chamber tending to urge said tray in a direction from said contacts, said spring means being incapable of moving said tray when loaded with ice cubes but of sufficient strength to move said tray when empty.

4. In a tray for molding ice cubes having a plurality of partitions, partitioning walls between said partitions, means for freeing ice cubes from said partitions comprising electrical heating elements disposed within said partitions, terminals for said heating elements extending from said tray and protecting means covering said terminals.

5. In a device for freeing ice cubes, a tray for molding ice cubes, electrical heating elements for heating said tray, terminals on said tray for said heating elements, a chamber adapted to receive said tray and complementary terminals in said chamber adapted to register with the terminals on said tray.

10 15 In testimony whereof, I have hereunto set my hand.

EDGAR D. ROSENBERG.
